UNITED STATES PATENT OFFICE.

PERCIVAL F. KING, OF NEW YORK, N. Y.

PLIER WRENCH.

Application filed August 9, 1923. Serial No. 656,520.

To all whom it may concern:

Be it known that I, PERCIVAL F. KING, a citizen of Canada, and a resident of the city of New York, borough of Manhattan, in the county of New York and State of New York, have invented a new and Improved Plier Wrench, of which the following is a full, clear, and exact description.

This invention, aiming to provide an inexpensive, quick-adjusting, positive-grip wrench of the plier type, has the principal object to provide a plier wrench of the crossed-handle and locking-jaw and friction-gripped horn type, in which, particularly, the cost of manufacture of the various relatively movable parts carried directly or indirectly by the crossed handles will not be really prohibitive as heretofore, but, on the contrary, will be practically nominal.

Another object of the invention is to provide a plier wrench of the type just characterized, but which shall incorporate a novel and valuable means for frictionally gripping the horn when the horn-guiding jaw is rocked relative to the jaw from which the horn fixedly projects, and such a means adapted to have great efficiency in applying a relatively long gripping-force couple lengthwise of the horn at all spacings of the jaws on gripping a nut or the like within the range of adjustment of the wrench.

Still another object of the invention is to provide an improved jaw-face particularly adapted for use in connection with a plier wrench, that is to say, with a wrench wherein friction and wedging means or both are solely relied on to hold the jaws clamped tight to a clutched nut or the like.

The invention will be best understood from a consideration of the following detailed description when taken in connection with the accompanying drawings forming part of this specification; with the understanding, however, that such drawings illustrate, merely by way of example, several possible embodiments and principles of the invention, and that the invention is not confined to any strict conformity with the showing in the drawings, but may be changed and modified so long as such changes and modifications mark no material departure from the salient features of the

invention as expressed in the appended claims.

In said drawings:

Fig. 1 is a side elevation of one of such embodiments, with the jaws expanded almost to the revised maximum;

Fig. 2 is a view similar to Fig. 1, but showing the jaws closer together and engaging;

Fig. 3 is a fragmentary detail view, being a horizontal section taken on line 3—3 of Fig. 2;

Fig. 4 is a transverse vertical section, taken on line 4—4 of Fig. 2;

Fig. 5 is a side elevation, partially broken away and partially in section, showing another embodiment;

Fig. 6 is what may be termed a top plan view of the wrench of Fig. 5 but with the upper portion of the horn shown in transverse section according to the line 6—6 of said Fig. 5;

Fig. 7 is a view, on an enlarged scale, taken on line 7—7 of Fig. 5, and showing the lower or horn-anchoring jaw in top plan; and

Fig. 8 is a transverse section, taken on line 8—8 of Fig. 7 but on even a larger scale than said Fig. 7.

In Figs. 1 to 4, in which like numerals of reference designate like parts, 10 is the lower jaw which is shouldered as indicated best at 11 in Fig. 2, to provide a central longitudinal ear 12 for reception at its rear portion between the bifurcated end 13 of one of the pair of crossed handles 14 and 15; these handles, as is conventional, being interpivoted at 16, and the lower jaw 10, as has heretofore been suggested, being pivoted to handle 14 as at 17.

The upper jaw 18 is shouldered at opposite sides to provide a reduced ear 19 the rear portion of which is received within the bifurcated end of handle 15; and said jaw 18 and said handle 15 are interpivoted, as has heretofore been suggested, at 20.

The horn here employed, and indicated at 21, is U-shaped and comprises, as best shown in Fig. 4, a central bowl always overlying the top of upper jaw 18, while the legs of the U are identical in length and in shape. This horn thus presents the free ends of

the legs of the U, or the lower end portions thereof, since said legs are spaced apart a distance precisely equal to the thickness of ears 12 and 19, such that, on application of rivets 22, the horn may be anchored rigidly to lower jaw 10 and tight against shoulders 11, while the upper portions of the legs of the horn snugly yet freely slidingly embrace opposite sides of the ear 19 of upper jaw 18.

In the present case, the opposite edges of horn 21, and marked 23 and 24 in Figs. 1 and 2, are given slight substantially parallel curvatures, so that the edge 24 of each leg of the horn convexly faces the curved forward edge 25 of handle 15 located at one or the other side of ear 19 of the upper jaw, and so that each edge 23 of each leg of the horn concavely faces the shoulder wall formed on one side or the other of the upper jaw to establish ear 19 thereof. Each of these shoulder walls is identically curved as at 26. As will be understood in a moment, however, the edges 23 and 24 of the horn legs or either of such edges may be varied considerably in curvature, or may even be made straight, provided the co-acting friction-gripping surfaces provided for the horn legs by the elements 25 and 26 on opposite sides of the wrench are compensatingly varied.

These edges, walls or surfaces 25 and 26 constitute the friction-gripping or oppositely co-active wedging elements for acting on the curved walls, edges or surfaces of horn 21 to impose a turning and hence gripping, clamping or wedging couple thereon, whenever upper jaw 18 is forcibly very slightly uptilted relative to an interposed object, such as the nut 27 of Fig. 2, on a squeezing together of the palm-held portions of handles 14 and 15 sufficiently first to cause the jaws to seize such nut and then to tend to advance parallelly into a closer adjacency than the presence of the nut permits. Such co-active friction-gripping surfaces have been heretofore proposed by me, in U. S. Letters Patent No. 1,438,442, granted December 12, 1922. But in the construction there disclosed, friction-gripping surfaces somewhat analogous to the present surfaces 25 and 26, are formed on the front and back walls of a vertical tunnel-like slot cut through the upper jaw. In other words, in said patent the equivalents of the present surfaces 25 and 26 are relatively immovable at all times, a conception distinctly the contrary of that underlying the present invention. And, further, the so-called equivalent relatively immovable surfaces of said patent are really not at all the equivalents of the surfaces 25 and 26 here. This is so because such surfaces of such patent are not smoothly convexly curved or indeed really curved at all, nor are they plane or substantially plane, but

instead are made up of a plurality of longitudinal subdivisions each of which is substantially plane, thus to present a distinct lateral ridge or mere line-contact-gripper for the horn where such subdivisions join. Such a mere line-contact-friction-grip relative to the horn is not as positive and reliable, nor as long-lived, as a plane or surface contact. Above and beyond all these considerations, however, the surfaces 25 and 26 of the present invention are relatively movable and thus moved each time one jaw of the wrench is moved toward or away from the other. As a result, whenever the handles 14 and 15 are squeezed together to move the jaws toward each other, the surfaces 25 of handle 15 move relatively to the surfaces 26 on upper jaw 18, and both sets of surfaces 25 and 26 move relative to the sets of surfaces 23 and 24 of the horn; and it will be noted that while the horn and the upper jaw slide relatively, and the lower jaw and handle 14 rock relatively, the upper jaw and its surfaces 26 rock not only relatively to the horn but to the surfaces 25 carried by handle 15. And it is partially as a result of all these simultaneous and relative rotational and translational movements of the several parts, that, as I have found in practice, surfaces 25 and 26 may be smoothly and very slightly convexly curved as clearly shown in Figs. 1 and 2. That is to say, I have discovered that both the relatively movable sets of friction-gripping surfaces 25 and 26 may be shaped to present convex curvatures as just characterized, each of which at no point along its length has a distinct change of direction readily perceptible as such at that particular point. Otherwise stated, a distinct lateral ridge is not presented by either surface 25 and 26; and thus, at practically all adjustments of the jaws, from fully open position to fully closed position, the friction-gripping surfaces for the horn 21 act to squeeze rather large areas thereof against opposite sides of the horn immediately on squeezing the jaws tight against the nut or the like interposed between them. These new friction surfaces, of course, do not interfere at all with a ready release of the jaws, once the long-arms of the handles 14 and 15 are pushed slightly apart; indeed, such surfaces permit even a readier and smoother release than heretofore. The curvatures of the surfaces 25 and 26 are not arcuate or circular, and instead are given an aberrancy of curvature, as the latter term is used in mensuration. Each of these surfaces represent some sort of a compound curve; what is commonly known as an indeterminate curve, e. g., a curve indeterminate except by empirical ascertainment, since such curve cannot, as the invention is now understood, be said

to be any geometrical or algebraic curvature definable by an equation. It will be noted that an important characteristic of the curve of each of such surfaces 25 and 26, too, is the fact that the curves are very shallow; which is to say, imagining that the curves are arcuate or circular, they are struck from a radii so large that the lengths of the curves would represent but very small fractions of the entire circles generated by such radii. Satisfactory results are attained even when the surfaces 25 and 26 so closely approach the plane as merely to allow sufficient change of angle to permit free travel of the horn.

In a construction pursuant to the invention as just described, it has been noted in connection with tests with a full-size working model, that the centers of pressure of the surfaces 25 and 26 at opposite sides of the horn are spaced longitudinally of the horn, in all adjustments of the jaws when gripping interposed objects of different sizes, a very much greater distance than are the mere lateral ridge-grippers of the somewhat analogous but relatively immovable surfaces of the patent aforesaid; and it has been further noted, in similar tests, that such distance, in the present construction, is practically the same in all degrees of separation of the jaws, except for a slight but appreciable, and hence desirable, augmentation of such distance at spacings of the jaws where the long arms of the handles 14 and 15 are so spaced as to give the least efficient palm-grip thereof.

It will have been appreciated from the foregoing that one of the most important contributions of the present invention toward the attainment of the object of a plier wrench of great efficiency in use, is the carriage of surfaces 25 or an analogue on one of the handles 14 and 15, thus to make the surfaces 25 and 26 relatively movable as above described. This very construction, further, makes possible the attainment of one of the most important objects of the present invention, the one first hereinabove recited, to wit, to provide a plier wrench which may be manufactured at other than a prohibitive cost, indeed, at nominal expense. In this connection, it is pointed out again herein that the horn-engaging surfaces carried by the upper jaw in said patent are certain of the bounding walls of a tunnel-like vertical opening in the upper jaw. In manufacturing such an upper jaw, after drop-forging to external shape, the only possible way of machining such tunnel-like opening, which it was found had necessarily to be of non-circular cross-section and actually was required to be rectangular in cross-section if the lateral contact ridges characteristic as aforesaid of the analogues for the present

surfaces 25 and 26 were to be of sufficient length to act at all pursuant to the theory of the invention, was to subject the forged jaw to a broaching or milling operation, at a cost of approximately thirty cents for each jaw, and at a cost of at least twenty-five cents even with the most expensive and elaborate production tools and processes as now conceivable. In the case of the present invention, however, due to the U-shaped horn 21, with its legs embracing the plane parallel opposite sides of ear 19 of the upper jaw, and due to the fact that these opposite sides of such ear extend to the very inner end of the entire jaw, it will be seen that the upper jaw may be drop-forged not only as to its main form but also to provide the ear 19 as the result of such drop-forging operation, and that the necessity for any expensive forging or similar machining is entirely eliminated.

Now referring to the embodiment of Figs. 5 and 6, it will be shown that indeterminately curved friction-gripping surfaces according to the invention may be employed, broaching or similarly expensive machining operations relative to the upper jaw may be eliminated, and an equally satisfactory and practically as inexpensive a plier wrench may be provided, by the use of quite a different type of multi-leg horn structure for the lower jaw than that shown in Figs. 1 to 4.

In the case of said wrench of Figs. 5 and 6, said horn 30 is again a U-shaped one, but is arranged with its two legs in a plane running longitudinally rather than laterally of the wrench jaws. The jaws and handles are pivoted together at 28 and 29. The lower jaw 31 is bifurcated at its rear end to provide a pair of embracing ears 32 for a single central ear 33 of one of the crossed handles 34, while the upper jaw 35 is similarly shaped at its rear end to embrace a single leaf 36 on handle 37. Handles 34 and 37 are interpivoted as at 38. The bowl of the horn 30 here also lies above upper jaw 35, and therefore said horn, like the horn 21 of Fig. 1, incorporates stop means for predetermining the maximum amount of separation of jaws 10, and also means for always holding the two jaws substantially to parallelism and properly on their various pivotal mounts to hold the wrench always adapted for use pursuant to the invention. This is so, because while the leg of the U-horn marked 30' in Fig. 5 co-acts with friction-gripping surfaces 39 and 40 pursuant to the invention and one of which is carried by crossed handle 37 and so is movable relative to the other, the other leg of the horn passes through a tunnel-like passage 41 cut vertically through the upper jaw. This passage 41 has front and rear friction-gripping surfaces smooth-

ly convexly curved according to the invention, but obviously somewhat differently shaped from the surfaces 39 and 40 (more or less identical with the surfaces 25 and 26 of Fig. 1); it being kept in mind that said surfaces of passage 41 are relatively immovable at all times. But the point is, that said passage 41 does not require broaching, milling or similarly expensive machining operations for its establishment. This is due to the fact, as will readily be seen from an inspection of Fig. 6, that said passage 41 is substantially circular in cross-section at all points along its length and truly circular in cross-section for a certain portion of its middle length. The friction-gripping surfaces within passage 41 are of course necessarily obtained by enlarging such passage at opposite ends, longitudinally of jaw 35, so as to give slightly elliptical or oval cross-sections to passage 41 at the top and bottom portions thereof; but it will be understood that the real establishment of said passage is the result of a mere drilling operation, plus a special later filing operation or operations of inconsiderable expense. Thus, in the case of the embodiment of Fig. 5, as in the case of the embodiment of Fig. 1, the shaping of the upper jaw 35 is in the main if not entirely a drop-forging proposition, aside from inexpensive drilling and filling operations in the special case of the embodiment of Fig. 5; and that in neither of the preferred wrench structures of the present invention as herein illustrated, is there any necessity for providing a tunnel-like horn-engaging passage of large cross-sectional area and of polygonal cross-section as heretofore suggested, in said patent. This is so, because the friction-gripping surfaces of passage 41 are designed to have a much less degree of co-action with their leg of the U-horn than are surfaces 39 and 40 relative to their leg; further, the cross-sectional area of each of the two legs of the U-horn here provided may be very much less than the cross-section of the single spike-like horn heretofore proposed, with the result that the leg of U-horn 30 in passage 41 has a considerable amount of inherent resilient flexibility; and, further, due to the presence of a plurality of separately and simultaneously engageable lengths for the horn, to wit, the two legs thereof, the long surfaces of said legs engaged by the two pairs of simultaneously functioning friction-gripping surfaces, may be convexly curved laterally, yet nevertheless to insure that the wrench will work perfectly pursuant to the theory of the invention. That the last-mentioned result is attained by the exceedingly inexpensive and simple construction of Figs. 5 and 6, has also been demonstrated, by repeated tests with a full-size working model.

The structural description of the embodiment of Figs. 5 and 6 will have been fully described when it is pointed out that U-horn 30 is mounted at its lower end fixedly on lower jaw 31 by forcing as shown the free ends of the legs of the U-horn into a pair of straight parallel tunnel-like openings of circular cross-section, and by riveting, as at 42, one of said legs in place. It will further be noted that each of the two legs of the U-horn 30 are flattened parallel with the length of the wrench, as shown most clearly in Fig. 6; which feature, I have found, makes for better and easier action of the wrench, both in gripping and releasing, in the presence of a passage 41 substantially circular in cross-section as hereinabove explained. And in this connection it should also be pointed out that the bifurcated rear end of upper jaw 35, at the inner end of such bifurcation, is shaped to provide a somewhat similar passage, as indicated at 41^a in Fig. 6, by a similar drilling operation and similar minor filing operations or the like.

The subject-matter of Figs. 7 and 8, and here illustratively forming a feature of the wrench of Figs. 5 and 6, but which obviously may also form a feature of the wrench of Figs. 1 and 2, constitutes a feature of the invention which is most important in assuring a tight grip by the two wrench jaws, and an exceedingly long life for the gripping faces of such jaws despite the natural tendency of these gripping faces to wear due to relative rocking movements always occurring between the jaws and the seized object, each time the wrench is used. There is illustrated merely a gripping face construction for the lower jaw; but of course it will be understood that preferably the construction illustrated is that characteristic of the gripping face of each jaw. The new gripping face incorporates two main features, which act here in conjunction. One of such features is what I term the bird-bill structure and comprises a marginal rib 43, a groove 44 alongside and within said rib, and a substantially plane portion 45 above and beyond said groove but lower than the crest of said rib. In Fig. 8 portion 45 is shown as having a slight lateral convexity; and the term "substantially plane" as just used, is employed in a sense to include such a slight convexity, laterally or longitudinally or both. As shown in Fig. 7, the upper face of the jaw is lanceolate, and as will be seen from a comparison of Fig. 5, the entire contour of such jaw suggests a bird-bill. Rib 43, and also groove 44, hence resembles a long reverse curve, somewhat like a flattened ellipse, symmetrical on both sides of the longitudinal center line of the jaw. In practice, I have found that it is most desirable to make the maximum depth of groove 44 about $\frac{1}{16}$ " where the vertical distance be-

tween the crest of the rib and the top of the substantially plane portion 45 is $\frac{1}{64}$ ". The other feature of the new gripping-face is a structure which I conveniently term the 5 fingerprint-suction-grip. As will be seen from Figs. 7 and 8, this structure essentially comprises a plurality of non-straight grooves 46, one of which partially or wholly embraces another; and, as shown in 10 Fig. 8, with each groove of less depth than the adjoining groove which the first-mentioned groove embraces. In the present case, each groove 46 is, roughly, ovate, and the innermost groove completely embraces a 15 central suction-pit 47 of maximum depth. It will be seen that as to the grooves 46, their relative dispositions and depths may be described as follows, to wit, that the grooves are substantially elliptical and sub- 20 stantially concentric and decrease in depth as they increase in diameter. As will be seen from Fig. 8, such progressive outward de- 25 crease in depth of the grooves is partially accounted for by the slight convexity of the portion 45 of the bird-bill structure.

Several embodiments of the invention have thus been described with great particularity and detail, in an endeavor to bring out clearly the nature and importance of 30 the present contribution to the plier-wrench art; but it should be distinctly understood that, as hereinabove indicated, wide variations may of course be resorted to within the scope of the following claims.

35 In closing this specification, it is especially pointed out that the horn of the present invention is essentially a horn structure comprising a plurality of spaced leg members, whether formed as separate spike-like elements, or whether parts of a unitary element and then connected together above the upper jaw or below the lower jaw to form a substantially U-shaped horn or at both the points last indicated to form a substantially O-shaped horn. Also, it is especially pointed out that, whereas there is disclosed in the patent aforesaid a tunnel-like opening, that is, an opening having a transverse outline of unbroken continuity, or a 50 true transverse aperture, through the jaw which slidingly engages the horn, in the case of the present invention the horn, or at least one leg member of a horn-structure including a plurality of such leg members 55 as aforesaid, essentially engages an external surface subdivision of, or a channel-type recess on, the jaw last-mentioned. Such a recess, in the sense of the present invention, and as the term is used in the following 60 claims, is illustrated by that recess established in Fig. 1 as the result of the angular relationship between shoulder 26 and the meeting side face of ear 19, and is also illustrated by the recess established in Fig. 65 5 between surface 39 and the two ears of

the upper jaw extending rearwardly from said surface.

An important feature of the new plier wrench, and one highly recommended for proper working of the present invention, although not absolutely essential nor herein claimed, resides in so relating the parts and particularly the horn and the friction-gripping surfaces therefor that the wall-parts on and adjacent to the upper jaw which constitute guiding ways for the horn intermediate said surfaces, do not have face contact with the lengths of the horn lying opposite thereto, thereby to give a mere line contact between said wall parts and said 75 lengths of the horn, thereby in turn to preclude jamming of the wrench parts by trapped grease, grit, etc. Such a construction is of course illustrated in connection with Fig. 6, by the expedient of making the 80 tunnel-like opening or aperture 41 and channel-like opening or recess 41^a concave between the friction-gripping surfaces thereof and shaping each of the two legs of the U-horn 30 so as to be flattened on oppo- 85 site sides parallel with the length of the wrench, as hereinabove described. A similar result may be obtained in the case of the embodiment of Figs. 1 to 4, if, referring to Fig. 3, the opposite plane sides of ear 19 are 90 left as shown, and the legs of the U-horn 21 are shaped to have their faces which lie opposite these sides of the ear, laterally concave from end to end.

I claim:

1. A plier wrench including a pair of crossed handles, a pair of jaws each pivoted to one of said handles, a horn operatively associated with both jaws, and means carried by the wrench and including a friction-gripping surface carried by the upper jaw adapted to wedge the horn fast to both jaws when the handles are squeezed together and to release such wedging engagement when said handles are separated, said horn being U-shaped, the free ends of the legs of the U being fixed to the lower jaw, said legs slidingly engaging said friction-gripping surface and forming a part of said means, and the bowl of the U being located 105 beyond the upper jaw, said means also including a friction-gripping surface for the horn and carried by the handle to which the upper jaw is pivoted.

2. A plier wrench comprising a pair of crossed handles, a jaw pivotally secured to the free end of each of said handles, a horn carried by one of the jaws and embracing the other jaw, and a cam face formed on the end of one of the handles and adapted to engage said horn to produce a binding action between the horn and the pivoted jaws upon movement of the crossed handles in a direction toward each other.

3. In a plier wrench, a pair of crossed

handles, a jaw pivotally connected to the end of each handle, a U-shaped horn rigidly secured to one of said jaws and embracing the other of said jaws, a plurality of curved gripping faces formed on the jaw embraced by said horn and adapted for engagement with one side of said horn, and a

cam surface formed on the free end of one of said crossed handles and adapted to engage the horn to move the same into contact with the heretofore mentioned faces of the pivoted jaw. ¹⁰

PERCIVAL F. KING.
